Inventor

WILLIAM J. HEPPERLE

By his Attorney:

Paul L. Brownrigg

UNITED STATES PATENT OFFICE.

WILLIAM J. HEPPERLE, OF BLOOMFIELD, NEW JERSEY.

CARRIER-SPACING DEVICE FOR PNEUMATIC-DISPATCH SYSTEMS.

Application filed June 11, 1921. Serial No. 476,870.

To all whom it may concern:

Be it known that I, WILLIAM J. HEPPERLE, a citizen of the United States, residing at Bloomfield, in the county of Essex and State 5 of New Jersey, have invented certain new and useful Improvements in Carrier-Spacing Devices for Pneumatic-Dispatch Systems, of which the following is a specification.

10 This invention relates to carrier spacing devices for use in pneumatic conveyor systems.

In the operation of pneumatic dispatch apparatus in which the carriers are delivered 15 in succession from a pneumatic tube into selector mechanism designed to separate the carriers into two or more classes, it is necessary, in order that the operation of the selector mechanism be effectively performed 20 to provide for preventing the arrival of the carriers in the selector mechanism in uninterrupted contact with each other. Devices are already known for spacing apart the arriving carriers just before they reach the 25 selector mechanism and the object of this invention is to provide an improved device of this general nature and particularly to provide a device which will operate with a maximum degree of positiveness and will be 30 locked in its carrier interrupting position until released by the carrier in advance.

With this end in view the invention consists in the provision of a carrier stopping device which is moved into position to interrupt 35 the following carrier by the advance of any given carrier, the carrier stopping device being locked in interrupting position by the engagement therewith of the leading carrier and released from its locked interrupting position by the continued movement 40 of the leading carrier. By the time that the leading carrier has moved into engagement with the releasing means a sufficient distance has been provided between the successive 45 carriers to provide for the normal operation of the selector mechanism as the leading carrier enters therein. Meanwhile the following carrier which has been momentarily interrupted by the stopping or interrupting 50 device, continues its travel and in turn sets the interrupting device in interrupting position to provide a space between this carrier and the next adjacent following one. This operation is repeated with the arrival of 55 each successive carrier in the spacing mechanism with the result that the carriers are

caused to leave the spacing mechanism in spaced or separated order thereby insuring the effective operation of the selector mechanism.

In the drawing in which a preferred form of the invention is selected for illustration,

Figure 1 is a vertical section of a spacing device embodying the invention and showing a carrier arriving in the mechanism.

Figure 2 is a view similar to Figure 1 in which a carrier is shown about to leave the spacing mechanism and with a second carrier temporarily held against advance by the position of the spacing device.

Referring to the drawing there is shown at 1 the delivery end of a suitable pneumatic dispatch tube to which is attached a housing or casing 2 for the spacing mechanism. This mechanism consists of a carrier stopping member 3 pivoted at the point 4 in a housing 4 forming part of the main casing 2. The carrier stopping member 3 is provided with two arms 5 and 6 projecting in position to be engaged in alternation by the descending carriers 7 and 8. In the normal position of the carrier stopping member shown in Figure 1 of the drawing the upper carrier engaging arm 6 is shown in withdrawn position, this effect being brought about by the action of the retractile spring 9. At the same time the lower arm 5 of the carrier stopping member 3 is pushed forward into position to be engaged by the descending carrier 7 as will be seen in Figure 1.

In the operation of the device the descending carrier 7 engages the laterally extending arm 5 and swings the carrier stopping member 3 about the pivot 4 into the position shown in Figure 2 of the drawing. It will be seen that the arm 6 of the member 3 is spaced from the lower arm 5 by just the proper distance to cause the end of the arm 6 to engage the upper end of the carrier 7 as indicated in Figure 1. By means of this arrangement the arm 6 operates to push or kick the carrier 7 laterally into the exit end 10 of the casing 2, a fixed lug or projection 21 on the base of the casing 2 serving to restrict the movement of the lower end of the carrier 7 and thereby cause the carrier to topple over endwise in a reversed position into the conduit or outlet end of the casing 2.

Meanwhile the carrier stopping member 3 is locked into the position shown in Figure

3 by the engagement of a latch hook 11 provided on the under side of the arm 5 with a cooperating latch member 12 pivoted at 13 on a lug 14 and normally held in latch engaging position by means of the spring 15. The latching of the member 3 in the position shown in Figure 2 of the drawing causes the upper arm 6 of the member 3 to take a position extending into the path of a 10 succeeding arriving carrier 8 and momentarily checks further movement of the carrier 8 as will be clear.

In order to release the carrier 8 for further movement when the leading carrier 7 has proceeded a desired distance in its travel 15 toward the exit end of the casing, a latch releasing member 16 is provided which is pivoted at a point 17 on a lug 18 carried by the casing 2 and has a carrier engaging 20 end 19 projecting through a recess 20 in the casing 2 into position to be engaged and moved by the contact therewith of the carriers as they pass downwardly through the exit end 10 of the casing 2. It will be seen 25 that the engagement of the carrier 7 in Figure 2 with the latch releasing arm 16 causes the latch member 12 to be moved out of engagement with the latch hook 11 on the arm 5 whereupon the spring 9 acts to withdraw 30 the arm 6 from its interrupted engagement with the following carrier 8. It will be apparent that by this arrangement when a leading carrier is emerging from the exit end 10 of the casing 2 and arriving carrier is on 35 the point of beginning its entrance to the casing 2 so that a full interruption of the travel of the following carrier 8 is brought about which provides the desired spacing between succeeding carriers.

40 It will be seen that by the use of the mechanism described positively acting means are provided for bringing about an interruption in the travel of following carriers so that the positive and certain obtaining of the desired spacing function is invariably secured.

45 What I claim is:

1. A carrier spacing device for conveyor systems comprising a movable member adapted to be moved by a traveling carrier 50 into the path of a following carrier, means for locking the movable member in its interrupting position, and means operated by the first carrier in its continued travel for releasing the locking means to clear the path 55 of the following carrier.

2. A carrier spacing device for conveyor systems comprising a pivotally mounted member adapted to be swung by a traveling carrier into the path of a following carrier, 60 means for locking the pivotally mounted member in its path interrupting position, and means projecting into the path of the first carrier and operable by the engagement of the first carrier therewith to release the

locking means and permit the pivotally mounted member to clear the path of the following carrier.

3. A carrier spacing device for pneumatic dispatch systems comprising a pivotally mounted two-armed member, one of said arms being arranged to be engaged by the advancing end of a carrier to swing the other arm into the path of a following carrier, means for locking the member in path obstructing position, and means engaged by the first carrier at a desired point in its travel for releasing the locking means to clear the path of the following carrier.

4. A carrier spacing device for pneumatic dispatch systems comprising a pivotally mounted unitary two-armed spacing member, one of said arms being arranged to be engaged by the advancing end of a traveling carrier to thereby swing the other arm into engagement with the other end of the carrier to push the carrier to one side, a conduit arranged to receive the displaced carrier, and said second arm being arranged to obstruct the path of a following carrier in its displacing position

5. A carrier spacing device for pneumatic dispatch systems comprising a pivotally mounted member, one end of said pivotally mounted member being arranged to be engaged by the lower end of a descending carrier, a fixed lug adjacent said end of said pivotally mounted member, said other end of said member being arranged to be swung into engagement with the upper end of said carrier to cause said carrier to topple over 100 said fixed lug into a reversed end-for-end position, a conduit arranged to receive said displaced carrier, and said second-named end of said member being arranged to obstruct the path of a following carrier in its displacing position.

6. A carrier spacing device for pneumatic dispatch tubes comprising a pivotally mounted member, one end of said pivotally mounted member being arranged to be engaged by the lower end of a descending carrier, a fixed lug adjacent said end of said pivotally mounted member, said other end of said pivotally mounted member being arranged to be swung into engagement with the upper end of said carrier to cause said carrier to topple over said fixed lug into a reversed position, a conduit arranged to receive said displaced carrier, said displaced second-named end of said member being arranged to obstruct the path of a following carrier, means for locking said member in said obstructing position, and means operable by said first-named carrier passing through said conduit to release said locking 120 means.

WILLIAM J. HEPPERLE.
